WITNESS:

UNITED STATES PATENT OFFICE.

JOHN WHITE JOHNSTON, OF ROCHESTER, NEW YORK.

GOLF-BALL HOLDER.

Application filed April 4, 1923. Serial No. 629,839.

To all whom it may concern:

Be it known that I, JOHN W. JOHNSTON, a citizen of the United States, residing at Rochester, in the county of Monroe and 5 State of New York, have invented new and useful Improvements in Golf-Ball Holders, of which the following is a specification.

This invention relates to holders for special articles, and has for its object the provision of a novel device for holding a plurality of golf balls while they are being repainted.

An important and more specific object is the provision of a device of this character 15 which includes a support from opposite ends of which radiate pairs of spring arms terminating in points adapted to engage against opposite sides of golf balls for holding them during the process of repainting.

20 An additional object is the provision of a device of this character which will be simple and inexpensive in manufacture, convenient and time saving in use, efficient and durable in service and a general improvement in the

25 art.

With the above and other objects and advantages in view the invention consists in the details of construction to be hereinafter more fully described and claimed and illustrated in the accompanying drawings, in 30 which:

Figure 1 is a perspective view of the device in use,

Figure 2 is a longitudinal section.

35 Referring more particularly to the drawings I have shown my device as comprising an elongated support 10 which might be solid or hollow and which may be of any suitable material and of any desired cross 40 sectional configuration. Radiating from the ends of this support are pairs of spring arms 11, the free ends of each pair being directed toward each other as shown at 12 and being pointed as indicated at 13. The actual man-

ner of securing the arms upon the support 45 10 may of course vary within wide limits but in the present instance I have shown the support as being tubular with the inner end portions of the arms engaged there within and soldered. This detail is however only 50 for the sake of illustration as other securing means might be equally advantageous. It is to be noted that the arms are so arranged that the ends 12 thereof are in alignment.

In the use of the device golf balls to be 55 repainted are engaged between the points 13 of each pair of spring arms and it will be observed that the balls are thus held firmly while still being capable of being rotated to a certain extent so that all sides thereof may 60 be reached in the process of painting.

From the foregoing description and a study of the drawings it will be apparent that I have thus provided a simply constructed and consequently inexpensive holder which will be a great time and labor saver for the purpose specified and which will be a distinct convenience.

While I have shown and described the preferred embodiment of the invention it is of 70 course to be understood that I reserve the right to make such changes in the form, construction and arrangement of parts as will not depart from the spirit of the invention or the scope of the subjoined claim. 75

Having thus described my invention I claim:

A device of the character described comprising a hollow central support, closure members in the ends thereof, and pairs of 80 arms having right angular extensions at their ends engaged within said closure members, said arms radiating from the support and terminating in extensions directed toward each other for engagement with diametrically opposite points of balls. 85

In testimony whereof I affix my signature.

JOHN WHITE JOHNSTON.
